(57) **CLAIM**

The ornamental design for a cosmetology safety glove, as shown and described.

DESCRIPTION

FIG. 1 is a rear view of my new, original and ornamental design for a cosmetology safety glove;

FIG. 2 is a front view thereof;

FIG. 3 is a perspective view thereof;

FIG. 4 is a rear view of an alternative embodiment of the cosmetology safety glove;

FIG. 5 is a front view thereof; and,

FIG. 6 is a perspective view thereof.

The human hand shown in broken lines in the drawings illustrates the environment in which the design is used and forms no part of the claim.
